DENTAL AMALGAM MIXER

Jacob A. Saffir, Chicago, Ill.

Application December 27, 1938, Serial No. 247,820

3 Claims. (Cl. 259—82)

This invention relates to improvements in dental amalgam mixers.

An object of this invention is to provide an amalgam mixer which is capable of thoroughly and properly combining and mixing the alloy and mercury generally in use by dentists for the making of amalgam as it is employed to fill cavities in teeth.

A further object is the provision of an amalgam mixer whose action is such that it is not likely to overtriturate the amalgam as is frequently the case in present amalgamators, overtrituration being very unsatisfactory because it has a deleterious effect on the final expansion of the alloy.

A still further object of this invention is to provide a means whereby the dentist can, within certain limits, regulate the amount of time he wishes the amalgamator to consume in mixing the amalgam. This is an important point because amalgam sets rather quickly and must be used almost immediately after it is prepared; at the same time the final steps in filling most teeth call for sterilization and complete dryness which conditions it is usually impossible to hold for a very extended period. The dentist, therefore, strives to have his amalgam mixed and ready as near as possible to the time that he has completed his final toilet of the cavity. Heretofore, without an assistant to slowly triturate the amalgam in a mortar while the dentist was working on the cavity, this was next to impossible. With the present invention the dentist has considerable leeway for, within certain reasonable limits, he can adjust the speed to consume as much or as little time as he requires and will find the process completed just when he has completed the necessary preliminary steps.

This invention also enables the dentist to watch the action going on in the amalgamator; previous mechanical amalgamators having been so constructed as to render it impossible to watch the mass while it is being mixed. This visibility is often of the greatest importance because frequently through an oversight or miscalculation the dentist has neglected to add sufficient mercury to his mix. Such a mix has to be discarded. With applicant's device, this deficiency can be remedied while the apparatus is in operation, more mercury can be added very easily, and a usable mix result, eliminating the inconvenience and waste occasioned by an error which could not previously be rectified.

The attainment of the above and further objects of the present invention will be apparent

from the following specification taken in conjunction with the accompanying drawing forming a part thereof.

In the drawing:

Figure 1 is a transverse sectional view of an apparatus embodying this invention.

Figure 2 is a transverse sectional view of just the mortar and its immediate surroundings in an apparatus showing slightly different embodiments than those in Figure 1.

Figure 3 is a similar view to that of Figure 2, showing still another embodiment.

Figure 4 is also a view similar to that of Figure 2 and showing still another embodiment.

Like parts are designated by the same characters and symbols of reference in all the figures.

In the drawing, 5 designates a casing made of any suitable material such as Bakelite, glass, or metals of various kinds. It may be of any desired design or configuration, the design shown in Figure 1 being conveniently illustrative.

In Figure 1, the casing 5 comprises a base, side-walls and a top. On the top there is an opening in which is set a glass mortar 6, kept in place by the retaining member 7. The mortar is removable and when set in position for operation it is so placed that the square indentation 15 in the bottom of the glass mortar engages the square head 14 on the upper end of the shaft 12a coming from the motor 12 which has a supporting member 6 which is fixed to the casing.

Hinged members 13 and 13a keep the mortar from raising up and disengaging from his driving means. To remove the mortar these hinged holders are opened up and the mortar can easily be lifted from its position and emptied. At 9 is a metallic magnetically attractive ball shown here directly above the electromagnet 10. The electromagnet is connected by means of the wires 3 and 3a to a switch outside of the casing, which, when closed energises the magnet and creates a downward pull on the ball 9.

To operate the amalgamator, the motor 12, which is connected by means of the wires 12c to a rheostat so that variable speeds are possible, is set in motion at the desired speed. This causes the mortar to revolve with everything in it, with the exception of the ball 9 which is being attracted and held at the closest point to the magnet. The ball, however, although remaining at the position mentioned and not varying more than a fraction of a centimeter from that spot does have imparted to it a roll in the direction opposite to the direction of the mortar. It can be seen, therefore, that when alloy and

mercury are placed in the mortar, 8, and the mortar is made to rotate, the alloy and mercury will be run over by the rolling ball 9 every time it gets to the point over the magnet. The ball not only exerts its own weight when passing over the alloy and mercury, but also causes considerably more pressure due to the effect of the pull of the magnet. This pull can, of course, be varied by the amount of current to the magnet and the size of the magnet.

The amount of time required to amalgamate the alloy and mercury is dependent on the speed of the motor which may be varied from about 100 to 500 or even 600 revolutions per minute, and the weight of the ball and pull of the magnet which can also be made variable by reducing or increasing the current supply to the electromagnet. This factor of magnetic pull can not be varied where a permanent magnet is employed.

In Figure 2 at 16 is shown a claw-like scraping member hinged on an adjustable post 17. This is a thin scraping device which is lowered in the mortar 8 and acts to prohibit the caking of the alloy and mercury on the bottom of the mortar. The use of this device is optional with the dentist. It is not an absolute requirement and its chief utility is where very large quantities of alloy and mercury are to be amalgamated. In Figure 2, 10a is a permanent magnet.

In Figure 3 the mortar 8 rests in a holder 1a which is mounted on an eccentric shaft 19 by means of shaft 18 from the holder 1a. When the shaft 19 is in motion the movement of the mortar 1 is eccentric and the ball 9 is given a rolling motion which is very rapid and the effect of its rolling over alloy and mercury is to cause its amalgamation.

Figure 4 represents a mortar 8 which is stationary and a steel ball 9 attached by a magnet 10b. This magnet is attached by means of 19 to a rotating shaft 20, which, when rotating imparts the same motion to the magnet 10b which pursues a circular course below the bottom of the mortar 8. In turn the ball 9 follows the magnet 10b and by its rotation and pull from the magnet causes the amalgamation of the alloy and mercury.

It can be seen that by similar means an electromagnet can be attached to a movable shaft

and operated like the magnet illustrated in the above paragraph.

I have herein before described the preferred embodiments of this invention, but I desire it to be distinctly understood that I am aware that many changes may be made therein and parts omitted without departing from the scope of my invention as defined in the subjoined claims.

Having thus fully described this invention I claim as new and desire to secure to myself by Letters Patent of the United States:

1. A device for mixing and triturating, comprising a mortar, a triturating ball loosely disposed within said mortar and being ferro-magnetically responsive, means below the bottom of said mortar for generating a magnetic field within at least a portion of the mortar interior to force said ball tightly against the bottom mortar surface, and means for obtaining relative motion between said mortar on the one hand, and said ball and magnetic field generating means on the other hand, said ball being adapted to be maintained within the generated field and roll with respect to the mortar surface and be pressed tightly against said surface to triturate any material within said mortar.

2. A device for mixing and triturating, comprising a mortar, a triturating ball loosely disposed within the mortar and being ferro-magnetically responsive, means below the bottom of said mortar for generating a magnetic field within at least a portion of the mortar interior to force said ball tightly against said mortar bottom, a scraping member depending in said mortar and normally disposed at a region remote from said ball, and means for obtaining relative motion between said mortar on the one hand and said ball and magnetic field generating means and scraper on the other hand, said ball being adapted to be maintained within the magnetic field and roll with respect to the mortar surface and be tightly pressed against said surface to triturate any material within said mortar, and said scraper being adapted to break up any agglomerations of material within said mortar.

3. The structure of claim 1, wherein the mortar travels with respect to the ball and magnetic field generating means in a circle eccentric with respect to the center of said mortar.

JACOB A. SAFFIR. 50
